JOHN H. SENGSTAKEN, OF BROOKLYN, NEW YORK, ASSIGNOR TO FOSTER WHEELER CORPORATION, OF NEW YORK, N. Y., A CORPORATION OF NEW YORK

STEAM PLANT

Application filed September 7, 1929. Serial No. 390,945.

My invention relates to steam boilers.

In steam boilers, the tendency is toward higher steam pressure, and consequently higher steam temperatures. The result of this is that products of combustion give up less of their heat differential to water and steam in the boiler proper and more heat must be taken out of the products of combustion after they leave the boiler proper.

10 Devices for absorbing this lower temperature range of heat are generally known as economizers. Economizers include both air preheaters, in which products of combustion preheat air supplied to the furnace, and feed

15 water heaters, in which the feed water is preheated before entering the boiler proper. Air preheaters may be used alone and feed water heaters may be used alone.

Air preheaters have steel plates which are heated to high temperatures by the products of combustion. With high temperatures of products of combustion entering the air preheater, there is danger of corrosion. Plants are now being designed with temperatures of over 1,000° F. for the gas leaving the boiler proper. This temperature is likely to oxidize the plates of an air preheater. The gas inlet temperature for an air preheater should preferably be under 800° F.

20 The large amount of heat available in products of combustion of 1,000° F. or over, when applied entirely to the heating of feed water, has a tendency to cause excess steam formation in a feed water heater particularly when the feed water is supplied to the economizer at high temperatures as is becoming usual practice.

In order to obtain a maximum effect from the products of combustion and, at the same time, eliminate these difficulties, I propose to combine a feed water heater and an air preheater in a boiler installation in such a manner that the feed water heater eliminates the above described difficulty as to the pre-

25 heater and the preheater eliminates the above described difficulties as to the feed water heater.

In accordance with this purpose, I arrange the air preheater between two sections of a feed water heater so that the temperature

of the products of combustion is suitably reduced by contact with tubes carrying feed water before entering the air preheater and the air preheater suitably reduces the temperature of the products of combustion entering the feed water heater proper.

The invention is diagrammatically illustrated on the accompanying drawing whereon:

Fig. 1 is a diagrammatic view of a steam generating unit embodying the invention; and

Fig. 2 is a cross-sectional view taken on the line 2—2 of Fig. 1.

On the drawing, reference character 10 designates a boiler comprising the usual water tubes 11 and steam and water drum 12. The tubes are situated within a combustion or furnace chamber 13. A stoker 14 is indicated as a source of products of combustion.

Air for combustion is supplied through air duct 15. Solid or liquid fuel co-acts with the air to form hot products of combustion which heat the water tubes and produce steam. The products of combustion leave the boiler proper through flue 16, having been partially cooled by contact with the boiler surfaces.

Other factors remaining constant, the higher the pressure of steam withdrawn from the boiler, the higher the exit temperature of the products of combustion. This is because saturated steam must have higher temperature at higher pressure. Assume that the temperature of gases entering flue 16 is 1070° F.

In flue 16 is a feed water heater composed of a first section 17 and a second section 18. Between these sections is an air preheater 20.

Feed water is supplied from a pump at 90 suitable pressure through conduit 21 into header 22. A plurality of tubes 23 extending across the flue are connected to header 22. Tubes 23 constitute a horizontal row of tubes. Above row 23 is another row 24 of the same number of tubes. The tubes of row 23 are individually connected to individual tubes of row 24 by members 25. Section 18 of the feed water heater comprises a plurality of rows of tubes, each row containing the same 100

number of tubes and the rows being connected for series flow in a plurality of parallel paths. Extended surface rings may be applied to the feed water heater tubes. The parallel paths of flow through section 18 join again at header 26.

10 A conduit 27 connects header 26 with a header 28. Header 28 is part of first feed water heater section 17. Another conduit 33 connects header 26 with steam and water drum 12. A valve 34 is interposed in conduit 27. A valve 35 is interposed in conduit 33. Assume that valve 34 is open and that valve 35 is closed.

15 Section 17 likewise is made up of a plurality of rows of tubes connected to give series flow between corresponding tubes of the respective rows and parallel flow in the rows. Feed water after passing through the tubes 20 of section 17 enters header 29 and thence passes through one or more conduits 30 into the steam and water drum 12 of the boiler proper. A valve 36 is interposed in conduit 30.

25 The number of rows of tubes in section 18 is appreciably greater than the number of rows of tubes in section 17. With like tubes and like rows in the two sections, the number of rows in the second section is preferably at 30 least twice the number in the first section.

35 The air preheater may be of any of various types, a plate type air preheater being indicated by way of example. Referring to Fig. 2, products of combustion pass downwardly through passages 31. Air enters through duct 32, passes through passages 38 and thence passes through duct 15 to the boiler furnace. Heat is transferred from the products of combustion to the fresh air through 40 the plates of the air preheater.

45 The various surfaces are preferably calculated and designed so that, with an exit flue gas temperature of about 1070° F., the first feed water heater section will reduce the temperature of the products of combustion to about 750° F. which is below the temperature which will cause oxidation and so that the 50 temperature of the products of combustion leaving the air preheater and entering the second feed water heater section will be about 675° F. Even though the temperature of feed water supplied through conduit 21 is 300° F. or more, the feed water heater will not form steam or form steam to any excessive 55 extent. Due to the air preheater, the temperature of the water entering the first feed water heater section is sufficiently low so that, by providing a suitable velocity of flow, steaming is prevented or diminished.

60 Instead of having series flow, the feed water may pass in parallel through sections 17 and 18. In such case water passes through conduit 21 into feed heater section 18 and thence through conduit 33 to the steam and 65 water drum, the valve 34 being closed. Feed

water passes through conduit 37 into header 28 and through section 17 and thence through conduit 30 into the steam and water drum. By means of this arrangement any desired temperature may be maintained in flue 16 70 at the hot gas entrance to the air preheater by controlling the relative rates of flow of water through conduits 21 and 37.

75 It will also be evident that the feed heater sections may be connected in series and have feed water supplied both at inlet 21 and inlet 37 in which case desired temperatures can also be maintained by suitable regulation of the flow of feed water.

80 It will be understood that the invention is not limited to particular structure. The boiler proper may be of any type and it may be heated in any manner. The flow through the feed water heater may be down instead of up; though I prefer counter-flow. Tubes 85 may be bare or have extended surface and may be otherwise connected than above described. Instead of one connection 27, there may be as many connections as tubes in a row so that there is full series flow between headers 22 90 and 29.

What I claim is:

1. A steam plant comprising a boiler, a flue for conducting products of combustion from said boiler, an air preheater interposed in said flue and feed water heater sections in said flue on each side of the air preheater, one of said sections being in advance of said preheater and the other of said sections being behind the preheater with respect to gas flow through said flue. 100

105 2. A steam plant comprising a boiler, a flue for conducting products of combustion from said boiler, an air preheater interposed in said flue, a first feed water heater section in said flue, a second feed water heater section in said flue, means to supply feed water to said second feed water heater section, means to conduct feed water from said second feed water heater section to said first feed water heater section and means to conduct feed water from the first feed water section to the boiler, the arrangement being such that the products of combustion first heat feed water in the first feed water heater section, then heat air for combustion in the air preheater and then heat feed water in the second feed water heater section. 110

115 3. A steam plant comprising a boiler, a flue for conducting products of combustion from said boiler, an air preheater interposed in said flue, a first feed water heater section in said flue, a second feed water heater section in said flue, means to supply feed water to said second feed water heater section, means to conduct feed water from said second feed water heater section to said first feed water heater section and means to conduct feed water from the first feed water section to the boiler, the arrangement being 120

such that the products of combustion first heat feed water in the first feed water heater section, then heat air for combustion in the air preheater and then heat feed water in the second feed water heater section, the 5 heat transmitting surface of the second feed water heater section having an area appreciably greater than the surface area of the first feed water heater section.

4. The method of extracting heat from a 10 stream of flue gases which comprises successively extracting high temperature heat due to cooling by feed water, extracting intermediate temperature heat due to cooling by air 15 and extracting lower temperature heat due to cooling by feed water.

5. A steam plant comprising a boiler, a 20 flue for conducting products of combustion from said boiler, an air preheater interposed in said flue, feed water heater sections in said flue on each side of the air preheater, one of 25 said sections being in advance of said preheater and the other of said sections being behind the preheater with respect to gas flow 30 through said flue and conduits connecting the feed water heater sections with each other and with the boiler and valves in said conduits providing flow of feed water in parallel through the feed water heater sections 35 and to the boiler and in series through the feed water heater sections and to the boiler.

6. A steam plant comprising a boiler, a 40 flue for conducting products of combustion from said boiler, an air preheater interposed in said flue, a first feed water heater section 45 in said flue, a second feed water heater section in said flue, means to supply feed water to said first feed water heater section, means to supply feed water to said second feed water heater section, means to conduct feed water 50 from said second feed water heater section to said first feed water heater section, means to conduct feed water from said second feed water heater section to said boiler and means to conduct feed water from the first feed water heater section to the boiler, the arrangement being such that the products of combustion first heat feed water in the first feed water heater section, then heat air for combustion in the air preheater and then heat feed water in the second feed water heater section.

7. A steam plant comprising a boiler, a 55 flue for conducting products of combustion from said boiler, an air preheater interposed in said flue and feed water heater sections in said flue on each side of the air preheater, one of said sections being in advance of said preheater and the other of said sections being 60 behind the preheater with respect to gas flow through said flue and the latter of said sections having a heat transmitting surface of appreciably greater area than the surface area of the former section.

8. The method of extracting heat from

flue gases which comprises passing said gases into heat exchange relation with feed water for a given length of time to extract high temperature heat, then passing said gases 70 into heat exchange relation with air to extract intermediate temperature heat and then passing said gases into heat exchange relation with feed water for an appreciably longer length of time than the aforesaid length of time to extract lower temperature 75 heat.
